WILLIAM LEWIS, OF UTICA, NEW YORK.

SPRING CUSHION.

Application filed November 5, 1924. Serial No. 747,929.

This invention relates to spring cushioned upholstering for the seats and backs of chairs, couches, davenports and the like, in which one or more sets of springs are assembled in a definite relation as a unitary article of manufacture ready for installation in chairs, couches or other articles of furniture, for receiving and supporting the padding and covering commonly used in upholstering of this character.

The method most commonly employed is to place the springs more or less symmetrical-
ly within the frame of the article of furniture with corresponding ends resting upon suitable supports of webbing or metal bars leaving their other ends disposed in a plane parallel with, but some distance beyond, the plane of the corresponding face of the frame, after which additional webbing and padding is placed upon the last named ends and its marginal edges drawn tightly toward and secured to the adjacent portions of the frame to produce the desired convexity of the exposed surface, following which the covering is placed upon the padded surface and its marginal edges firmly secured to the frame to complete the upholstering.

In other words, the finished surface of the upholstering is usually convexed and when the marginal edges of the padding and covering are drawn sufficiently tight to compress the adjacent portions of the springs to produce the desired convexity and fastened to the frame, the padding and covering are necessarily placed under continuous high tension resulting either in loosening the fastening means or tearing out the marginal edges of the padding and covering and the main object of my invention is to construct the spring unit assembly in such manner as to produce the desired convexity and thereby to lessen the strains upon the marginal edges of the padding and covering when installed in the frame of the article of furniture.

It is also well known that unless the springs along the margin of the upholstering and particularly those at the front of an upholstered seat where the pressure is greatest and most frequent are connected to distribute the load from one to the other they soon become more or less flattened or otherwise deformed thereby causing irregular and objectionable sagging and wrinkling of the adjacent portions of the padding and covering, and another object of the invention is to provide means whereby pressure upon any portion of

the marginal edge of the system of springs will be transmitted to adjacent marginal springs and thereby to reduce the liability of deformation of the upholstering as a whole.

A further object is to arrange the complete system of springs in sets so that the marginal springs may constitute one set and those within the marginal set will constitute another set and to arrange said sets so that each may have a limited action independently of the other.

A still further object is to encase the marginal springs in suitable sheathings of webbing and to provide the intermediate portions of said sheathings with extension flaps adapted to be secured to the adjacent portions of the frame of the article of furniture for assisting in holding the entire system of springs in definite relation to the frame.

Other objects and uses relating to specific parts of the device will be brought out in the following description.

In the drawings:—

Figure 1 is a top plan of a cushion seat made up as a unit and embodying the preferred features of my invention ready for attachment to a frame of an article of furniture for receiving the padding and covering.

Figures 2, 3 and 4 are enlarged sectional views of the same seat taken respectively on lines 2—2, 3—3 and 4—4, Figure 1.

Figure 5 is an enlarged perspective view of a portion of one side of the marginal set of springs showing the sheathings therefor and a portion of one of the flaps by which the sheathing may be attached to the frame of the chair or other article of furniture.

Figure 6 is a top plan of a modified form of my invention omitting the webbing and sheathing in which the outer edges of the marginal springs are held under compression by flexible ties to produce the desired convex surface of the entire system of springs.

Figures 7 and 8 are sectional views taken respectively on lines 7—7, and 8—8, Figure 6.

As illustrated in Figures 1 to 5 inclusive, the seat comprises an outer or marginal set of coil springs —1— and an inner set of coil springs —2—, all of said springs being arranged to extend in the same general direction with their axes substantially parallel and those of each set in spaced relation relatively to each other and to those of the other set so that they may be compressed and extended without friction one with the other.

These cushions are usually four sided and

either rectangular or nearly so in top plan, and are double convex in cross section and also in longitudinal section, the springs of the marginal set being somewhat shorter than those of the other set or compressed within the planes of the opposite ends of the springs of the other set to produce the desired convex surface of the cushion as a whole.

In Figures 1 to 5 inclusive the means for holding the springs of the marginal set in compressed relation with their opposite ends in planes some distance within the planes of the corresponding ends of the inner set, consists of tubular sheathings —3— of webbing and inner lining strips —4— preferably of the same material each compressing a row of the springs —1— as shown more clearly in Figure 5, the strips —4— being arranged in pairs for each row and those of each pair 20 stitched or otherwise secured together to form tubes each receiving one of the springs.

That is, the strips —4— are drawn across opposite ends of the springs of each row and are stitched together at —5— at both ends of 25 the row and also are drawn between the springs and stitched or otherwise secured together at —6— between the springs, the ends of the strips and portions thereof between the springs meeting substantially midway between the ends of the springs so as to form 30 the desired tubes or pockets for retaining the individual springs under similar compression and causing their ends to lie in substantially flat, parallel planes.

After each row of springs —1— are bound together, in the manner described, between the strips —4—, they are inserted into the tubular sheathings —3— which constitute additional means for holding the ends of the 40 springs under compression and within the planes of the corresponding ends of the springs —2— of the inner set. The sheathings —3— are preferably made of sheets of webbing extending the entire length of the 45 row of springs which it is adapted to embrace and are made into tubular form by folding the sheet upon itself substantially midway between its ends and then stitching the opposite halves together longitudinally along 50 the line —7—, Figure 5, the proper distance from the fold to form the desired tube and also some distance from the ends to form flaps —8— adapted to be turned upwardly, downwardly, or extended horizontally as may 55 be most convenient and efficient for attachment to the frame of the article of furniture and thereby to support the marginal series of springs in proper relation to said frame, the lines —7— of stitching being preferably 60 located substantially midway between the ends of the springs and at the outer sides thereof adjacent the frame not shown to which the flaps —8— are to be attached.

The marginal springs —1— are preferably 65 cylindrical or of uniform diameter from end

to end and are held in more or less fixed spaced relation by inner and outer marginal frames —9— and —10— near one end and an additional marginal frame —10'— near the other end together with inner and outer intermediate frames —11— and —12— all of which frames are preferably made of wire and extend continuously along the four sides of the marginal set of springs, and sheathings —3— to which they are fastened by cords or equivalent fastening means to hold the frames and adjacent portions of the sheathings in reasonably fixed relation. The wire frames —9— and —10— and also the frames —11— and —12— are located respectively at the inner 70 sides and outer sides of the springs —1— while the frame —10'— is located at the outer side of the springs, the frames —11— and —12— being disposed substantially midway between the ends of the springs and substantially parallel with the remaining frames —9—, —10— and —10'—.

The central portions of two of the opposite sides of the inner frame —11— are connected by a wire tie rod —13—, while the central 75 portions of the remaining two sides of the same frame are connected by an additional tie bar —13'—.

In a similar manner the central portions of two of the opposite sides of the outer intermediate frame —12— are connected by a tie rod —14—, said tie rods —13— and —14— serving also as braces to hold the adjacent portions of the frames to which they are attached against undue inward or outward 80 movement, the tie bars —13— and —13'— being connected at crossing by a wire ring —15— to hold them against relative movement.

The springs —2— of the inner set are preferably double conical and somewhat longer than the springs —1— so as to extend beyond the opposite ends thereof for producing the desired convexity of the opposite faces of the cushion as a whole, said springs being preferably arranged in lengthwise and transverse rows and are supported at one end by strips —16— and —17— of webbing and an additional sheet —18— of the same material, the strips —16— and —17— crossing each other 100 at substantially right angles at the adjacent ends of the springs and extended to the corresponding sides of the frame —10'— where they are firmly secured by cords or other suitable fastening means.

The sheet webbing —18— is co-extensive with the adjacent side of the cushion and has its marginal edges secured by cords or other suitable fastening means to the frame —10'— across the outer faces of the webbing strips —16— and —17— thereby combining with said strips to form a flexible support for the adjacent ends of the springs —2—.

The other ends of the springs —2— are surrounded by a marginal wire frame —19— 115

and are secured to the adjacent portions of said frame by clips —20— and are also connected to each other by chains or other flexible ties —21—, the four sides of said frame —19— 5 being also connected to the frame —9— by chains or flexible ties —22— arranged in spaced relation throughout the lengths of said frames —19— and —9—.

In Figures —6—, —7— and —8— is shown 10 a spring cushion similar to that previously described in that it is composed of a marginal set of springs —1— and an inner set of springs —2—, the latter being preferably double conical and of greater length than 15 the springs of the marginal set which are preferably cylindrical and of uniform diameter from end to end and relatively shorter than the intermediate springs —1— to produce the desired convexity of the opposite faces of 20 the cushions. A pair of wire frames —10— and —10'— extend continuously around the marginal set of springs near the ends thereof and in spaced parallel relation, said frames being connected at regular intervals through- 25 out their lengths by chains or other flexible ties —3— to hold said frames and the ends of the springs within the planes of the corresponding ends of the intermediate springs —2— and still allow the free flexing action 30 of the marginal set of springs independently of the springs of the inner set.

The opposite ends of the springs —1— are 35 connected by clips —20'— to adjacent portions of the corresponding frames —10— and —10'— for holding said ends of the springs in relatively fixed relation to the corresponding frames.

The adjacent sides of the springs —1— are 40 also connected to each other by chains or other flexible ties —23—, while the adjacent sides of the intermediate springs are connected to each other by flexible ties such as chains —21'—, the intermediate springs adjacent 45 to the outer marginal springs being connected by additional flexible ties as chains —22'—, thereby establishing flexible connections between corresponding ends of the intermediate springs and those of the marginal set of springs and permitting the springs of 50 either set to act independently of those of the other set.

It will be noted that in both forms of this 55 invention the springs of the intermediate set are relatively longer than those of the marginal set and that the axial extension of the springs of the marginal set is limited either by the tubular sheathings —3— as shown in Figures 1 to 5 inclusive or by the flexible tie members —3'— as shown in Figures 6, 7 60 and 8 thereby forming a spring cushion with opposite convex faces and in which the springs of the inner set are free to compress under load and to expand under their own tension independently of the springs of the

outer set by reason of the flexible connections 65 between both sets.

It will also be obvious that the wire frames extending around the marginal edge of either set near the ends of the corresponding springs and their connections with said 70 spring cases will receive any load which may be applied to any one or more of those springs to be transmitted to others of the same set and tend to keep the ends of the springs of that set in substantially the same plane, particularly when the load thereon is removed, 75 all of which assist in preserving the symmetrical contour of the upholstering.

Each of the springs —1— of the outer marginal set is fastened to the fabric tube —3— 80 and to the outer wire frame —10— by loops —24— which preferably form parts of a continuous cord —24'— extending along the four sides of the wire frame —10—.

The adjacent sides of the springs —1— are 85 also secured together and to the sheathing —3— by loops —25— forming parts of a continuous cord —26— which also extends along the four sides of the sheathings —3— as shown in Figure 1.

The inner edges of one end of the springs —1— are also attached to the adjacent portions of the sheathings —3— and to the inner wire frame —9— by loops —27— forming parts of cords —28—, Figure 1 which also 90 extends around the four sides of said frame —9— and together with the cords —26— and —24'— assist in holding the frames —9— and —10— and adjacent portions of the sheathings —3— in substantially fixed 100 relation to the adjacent end of the springs —1—.

The ends of the fabric strips —16— and —17— and the marginal edges of the fabric sheet —18— may be fastened by similar cords 105 to the marginal wire frame —10'— and to the adjacent portions of the sheathings —3— and springs —1— to hold those parts in relatively fixed relation, the lower ends of the springs —1— being also fastened by cords 110 similar to the cords —26— to the adjacent portions of the sheathings —3— to hold them against relative lateral movement in said sheathings.

What I claim is:

1. A spring cushion comprising an outer set of similar coiled springs arranged in parallel spaced relation around the marginal edge of the cushion, a pair of similar resilient wire frames extending around the marginal edge of the cushion in planes adjacent the opposite ends of said springs, ties connecting opposite ends of the springs to the adjacent portions of the frames, flexible connections between said frames arranged to normally hold the springs under approximately equal compression and to limit the separation of the frames under the expansive force of 120

115

120

125

the springs and permitting free relative movement of the frames and opposite ends of the springs toward each other, an inner set of similar coiled springs parallel with and 6 normally extending beyond the planes of opposite ends of the springs of the first-named set, and flexible members attached to one of said wire frames and extending across the corresponding ends of the springs of the inner set 10 for holding them under compression and permitting both ends to yield toward each other.

2. A spring cushion comprising an outer set of similar coiled springs arranged vertically side by side in parallel spaced relation 15 around the marginal edge of the cushion, a pair of similar resilient wire frames extending around the marginal edge of the cushion in planes adjacent the lower and upper ends of the springs, means for attaching the wire 20 frames to the springs, an inner resilient wire frame extending along the inner sides of the upper ends of the outer set of springs, means for attaching the inner wire frame to the ad-

jacent ends of the springs, an inner set of coiled springs arranged in vertical parallel 25 spaced relation to each other and to the outer set of springs and having their lower and upper ends normally disposed in planes some distance below and some distance above the corresponding ends of the outer set of springs, 30 a separate wire frame surrounding the upper ends of the inner set of springs, means for connecting the upper ends of the springs of the inner set with the last-named wire frame, additional means for connecting the upper 35 ends of the springs of the inner set to each other, connections between the last-named wire frame and the second-named inner wire frame, and flexible members attached to the lowermost outer wire frame and extending 40 across the lower ends of the springs of the inner set.

In witness whereof I have hereunto set my hand this 21st day of October, 1924.

WILLIAM LEWIS.
